DEVICE FOR STRAIGHTENING HAIR

Albert Shelby, Buffalo, N. Y.

Application June 22, 1937, Serial No. 149,644

8 Claims. (Cl. 132—31)

This invention relates generally to a device for treating the human hair and more particularly to a means for and method of straightening hair having a wavy or kinky character.

5 It has for one of its objects to provide a device of this character which is so designed and constructed as to effectually straighten virgin hair permanently in a convenient manner and without discomfort to the wearer.

10 Another object of the invention is the provision of a hair straightening device which is simple, compact and inexpensive in construction, and which embodies means for stretching the hair by tensioning it between slowly moving rollers and at the same time treating the hair to break down its structure and render it effectually responsive to the stretching process, and also means for treating the straightened hair with cold or refrigerated air for the purpose of contracting the hair after straightening.

15 Other features of the invention reside in the construction and arrangement of parts herein-after described and particularly pointed out in the appended claims.

20 25 In the accompanying drawing:

Figure 1 is a perspective view of my hair straightening device. Figure 2 is an enlarged central longitudinal section thereof. Figure 3 is a horizontal section taken in the plane of line 3—3, Figure 2. Figure 4 is a cross section taken substantially in the plane of line 4—4, Figure 2.

30 35 Similar characters of reference indicate corresponding parts throughout the several views.

In its general organization, this hair straightening device or apparatus is designed for use by hair dressers and the like and consists of a sectional frame or chambered member between which portions of hair to be straightened are inserted, such frame carrying slowly-moving rollers 40 between which the hair is properly stretched by a tensioning action transmitted by such rollers; means for treating the hair while undergoing stretching, such means consisting of steam or the like which acts to break down the hair structure and render it effectually responsive to the straightening process, the roller-carrying frame constituting a chamber for this treatment; and means whereby cold or refrigerated air is introduced into this chamber to contract the hair after 45 50 the straightening process.

55 Referring now to the drawing, depicting the preferred embodiment of my invention, the numerals 10, 10 indicate the companion sections of the main frame or chambered body of the device, and which carry the operating parts thereof.

These sections are hinged to each other as indicated at 11 so as to be readily opened and closed when desired, as when inserting a section of hair to be straightened and permitting its removal after straightening, suitable catches 12 being provided for holding the sections in closed sealing engagement during the straightening process. In order to insure a fluid-tight seal between the sections, their opposing edges may be provided with sealing strips 13 of rubber or like material.

This sectional casing forms a chamber within which the hair is treated and borne by each of the sections 10 are rollers 14 which are disposed crosswise thereof in predetermined spaced relation so that when the sections are closed the companion rollers are disposed in opposing relation to receive the hair to be straightened between them, these rollers functioning to stretch the hair by a more or less tensioning action created by the rollers. As shown in the drawing and particularly Figure 2, these rollers are preferably faced with rubber or like material, as indicated at 15, which is of a comparatively hard texture to effectively perform the stretching of 20

the hair and still accommodate the rollers to hair which may be of varying thickness. These rollers are adapted to be revolved at a comparatively slow speed during the straightening operation and for this purpose a flexible driving shaft 16 is provided which may be driven, from an electric motor or other source of power not shown, and which is directly connected to one of the rollers 14, say, the front one of the group. The 25

rollers of the upper group are revolved in the same direction and the rollers of the lower group are revolved in the opposite direction and to this end each roller carries a gear 17. The gear of the foremost driving roller meshes with a like 30

35 gear on its companion opposing roller, and journaled on the frame sections 10 between the remaining respective gears 17 are idler gears 18 which act to revolve the successive rollers in the same directions as the respective foremost driving

40 45 rollers. At its front or feed end, the sectional casing 10, 10 is provided with opposing plates 19 between which the hair is guided and directed into the casing. In using the device when the free ends of the hair have been properly introduced into the front end of the device motion is then transmitted to the rollers 14, the device thereupon traveling over the hair to simultaneously stretch and straighten it.

50 55 The sectional casing 10, 10 constitutes a treating chamber for the hair and during the straight-

ing

ening operation, steam or like solution is introduced into the chamber to break down the hair structure and render it effectually responsive to the straightening process. For this purpose a conduit 20 is provided which is connected at one end to a source of steam or like solution while its other end is connected at 21 to the casing 10. A valve 22 may be interposed in this conduit to control the flow of solution therethrough. If desired, the casing may be properly insulated to facilitate the ready manipulation of the device by the attendant.

After the straightening and the heat-treating processes have been performed on the hair, the hair is then subjected to cold or refrigerated air which acts to contract the hair after the virgin kinky or curly hair has been straightened. For this purpose a conduit 23 is provided which is connected at one end to a source of cold or refrigerated air while its other end is connected at 24 to the sectional casing 10, a suitable valve or cock 25 being interposed in the conduit to control the supply of fluid to the casing.

In order to render this device effectually useful in straightening new growths of hair after an individual has been initially treated, I provide the casing 10, 10 with openings normally closed by doors or closures 26, as shown in Figure 2. These closures may be hinged to the casing as indicated at 27 and provided with suitable packing 28 to insure a proper sealing of the openings by the closures when in their closed position. These closures may be located at different points along the length of the chambered casing 10 and when straightening a new section of hair the free or previously-straightened ends are passed through the openings so as not to come in contact with the straightening rollers 14.

I claim as my invention:

- 40 1. A device for straightening hair, comprising a sectional casing adapted to be closed in sealing engagement to provide a treating chamber, and rollers rotatably mounted in said casing and between which the hair to be straightened is passed.
- 45 2. A device for straightening hair, comprising a sectional casing adapted to be closed in sealing engagement to provide a treating chamber, a series of rollers applied to said casing in opposing relation to receive the hair to be straightened

between them, one set of rollers being borne by one of the casing sections and the other set of rollers being borne by the companion casing section, and means for transmitting motion to said rollers to rotate them in the same direction. 5

3. A device for straightening hair, comprising a chambered casing, hair straightening rollers mounted therein and between which the hair to be straightened is adapted to pass, and means for introducing a treating solution to said chambered casing. 10

4. A device for straightening hair, comprising a chambered casing, hair straightening rollers mounted therein and between which the hair to be straightened is adapted to pass, means for introducing a treating solution to the chambered casing during the straightening operation, and means for introducing a cold fluid to said chambered casing to contract the hair after the straightening operation. 15 20

5. A method of straightening kinky or curly virgin hair which consists in stretching the hair by subjecting it to a tensioning action, treating the hair during such stretching operation with a solution to break down the hair structure and render it effectually responsive to the straightening operation, thereafter subjecting the straightened hair to a cold or refrigerated fluid to contract the straightened hair. 25

6. A device for straightening hair, comprising a casing forming a treating chamber for the hair, and opposing, rotatable means mounted in said casing for operative engagement with the hair to exert a tensioning and stretching action on the hair. 30

7. A device for straightening hair, comprising a casing forming a treating chamber, and means movably arranged in said casing for guiding the hair therethrough and for exerting a tensioning and stretching action thereon. 35 40

8. A device for straightening hair, comprising a casing forming a treating chamber, and means movably arranged in said casing for guiding the hair therethrough and for exerting a tensioning and stretching action thereon, said casing having a normally-sealed opening therein for the passage of previously straightened ends of the hair. 45

ALBERT SHELBY.
